UNITED STATES PATENT OFFICE.

WALTER T. GODDARD, OF HAMILTON, ONTARIO, CANADA, ASSIGNOR, BY MESNE ASSIGNMENTS, TO LOCKE INSULATOR CORPORATION, OF BALTIMORE, MARYLAND, A CORPORATION OF MARYLAND.

STRAIN INSULATOR.

1,406,953.

Specification of Letters Patent. Patented Feb. 14, 1922.

Application filed April 4, 1916. Serial No. 88,814.

To all whom it may concern:

Be it known that I, WALTER T. GODDARD, of Hamilton, Province of Ontario and Dominion of Canada, have invented certain new and useful Improvements in Strain Insulators; and I do hereby declare the following to be a full, clear, and exact description of the same, reference being had to the accompanying drawings, forming a part of this specification, and to the reference-numerals marked thereon.

My invention relates to strain insulators of the general character employed for supporting high tension conductors, and embodying, in a broad aspect, a pair of metallic strain or tension members connected by one or more insulating sections or members, and it has for its purpose to provide an efficient combination and arrangement of parts possessing the necessary strength to withstand the heavy strains of a high tension line. A further purpose of the structure is to afford such a mechanical union between the insulating and strain members of each unit as to entirely obviate any destructive action upon the insulating member that would otherwise result from a difference between its coefficient of expansion and that of the strain member. An additional object of the invention is in providing a device which can be readily assembled and economically made, rendering it entirely practicable, while at the same time possessing all the requirements of insulators of the type mentioned. To these and other ends the invention consists in certain improvements and combinations of parts, all as will be herein-after more fully described, the novel features being pointed out in the claims at the end of the specification.

In the drawings:

Figure 1 is a sectional view showing the application of my improvements to an insulator of usual type, with the metal cap or upper strain member in the position in which it is placed upon the insulating member preliminarily to its attachment thereto;

Figure 2 is a similar view with the parts completely assembled;

Figure 3 is a horizontal sectional view on line 3^a—3^a of Figure 2;

Figure 4 is a side elevation of the completed structure;

Figure 5 is a sectional view showing the

manner of assembling the parts which unite or lock the inner strain member within the hollow portion of the insulator member;

Figure 6 is a similar view showing a further step in the operation;

Figure 7 is a view in elevation showing the form of locking member or plate employed as part of the retaining means for locking a strain member within the hollow portion of the insulator, and

Figure 8 is a sectional view of a modification.

Similar reference numerals in the several figures indicate the same parts.

In the construction of insulators of the general character already referred to, the more or less general practice has been to obtain a tight union between the insulator and strain members by cementing them together, but there has been considerable objection to this method owing to the fact that the strain member is usually formed of metal while the insulator member is of porcelain or similar material. The difference in the coefficients of expansion of the metal and insulating substance causes the latter to readily crack and break under changes of atmospheric conditions, and an additional disadvantage is found in the fact that dehydration of the cement binder takes place after the insulator has been in actual use for a time, causing deterioration of the insulators, and a lessening of its efficiency. Strain insulators, when in actual operation, are subjected to enormous loads, and it has been a difficult matter to so connect the metal cap or strain member, which is arranged upon the upper portion of the insulating member as to prevent the porcelain from yielding at one point or another, under certain strains, which is due to the localizing of the strain at one point of the insulating member, and this is overcome in my invention by distributing the load, or in other words, equalizing it around the different portions of the insulating member.

The improvements, which are now to be described more particularly, may be carried out in a variety of ways one of which is illustrated in the drawings, by way of example and includes an insulating member of the usual type formed of porcelain or similar non-conducting material, and including a top portion 1 and a skirt 2, while an annu-

lar groove or recess 3 is arranged at the base of the top portion for a purpose that will presently appear. Cooperating with the top portion 1 is a metal cap, carrying a lug 4 which is provided with the usual eye or opening 5 by which the structure may be connected to the cooperating strain member of the adjacent insulating unit. The cap is formed to provide a plurality of yieldable and independently movable retaining portions or sections which are brought into locking engagement with the insulating member, and in the present arrangement, the cap is split on a series of lines 6 from its lower edge upwardly, forming a series of yieldable spring arms or sections 7, each of which carries an inwardly projecting flange or enlargement 8 that engages the groove 3 on the insulating member. In the assembling of the cap upon the insulating member, the section 7 initially assumes the position shown in Figure 1, and may be forced inwardly in different ways, as for instance, by employing a compression ring or band 9, which may be forced down over the cap until it engages the outwardly projecting flange 10 at the lower edge thereof. This compresses or moves inwardly the yieldable sections of the cap until they assume the position shown in Figure 2 with the lugs 8 engaged. The band 9 is retained in its lowermost position by any desirable means, as for instance, locking pins 11, and 12 is a compression washer arranged in the groove 3 and against which the enlargements 8 are engaged. A compression washer 13 may also be employed between the upper portion of the cap and the upper portion of the insulator member, although this is not an essential part of the invention.

The insulator member is provided with the usual interior hollow portion 14 which is provided with a flange or shoulder 15 that is preferably inclined at an angle of 45° or less with respect to a plane at right angles to the normal direction of strain, the object of which arrangement will be more apparent presently.

The shoulder 15 affords a means for engaging and locking the strain member which cooperates with the interior of the insulator member, and which in the present embodiment includes a support consisting of a sleeve 16 having threaded engagement with a pin or post 17, the inner end of which carries the retaining means embodying a head 18 against which are secured a series of laminations in the form of plates or locking members 19, each being provided with an angular or inclined portion that cooperates with the inclined shoulder 15, as shown in Figure 1. Owing to the angle of the shoulder 15, the retaining means is prevented from wedging or freezing against it, by reason of strains exerted between the parts, and the parts are always free for slight separation under atmospheric changes or other conditions that would require such action, to prevent breaking the insulating member. The plates 19 are formed from blanks, as shown in Figure 7, and each provided with a series of slots or openings 20 extending radially from the periphery. The outer portion of the plate is bent inwardly, as shown at 21, in Figure 5, to reduce the diameter sufficiently to permit the plate to be inserted through the opening or hollow portion 14. In assembling the parts, the locking plates are positioned over the post 17, one at a time, each being provided with a central opening 22 that engages the said post. A plunger or stamping member 23 is then brought into engagement with the outer surface of the plate to force the latter inwardly until it assumes a more flattened position, and the inclined portion 19 is forced over the shoulder 18 of the insulating member. When the several laminated plates are in their completely assembled positions, they appear as shown in Figure 6, affording a plurality of laminated inclined or angular portions extending parallel to and supported on the shoulder 15, and maintain the strain member securely within the insulating member so that the parts cannot be separated except by breaking or destroying one of them. After the retaining means is properly positioned on the post 17, the sleeve 16 is then threaded thereon, the latter being open at its outer end to permit of inserting a tool for engagement with the slot 24, to effect rotation of the post with relation to the sleeve. The latter is held against movement relatively to the insulating member by means of a projection or lug 25 engaging a cooperating recess 26 upon the insulating member. The sleeve 16 and post 17 are in spaced relation to the walls of the insulating member, permitting expansion and contraction of the metal without distorting the porcelain and in order to prevent relative lateral movement of said parts, I employ a washer or spacing member 27, which is preferably of U-shaped formation in cross section and rests upon a shoulder 28 of the sleeve 16 to prevent its outward movement, while 29 is a shoulder formed on the insulating member and cooperating with the inner edge of said spacing device so as to hold the latter against movement inwardly of its normal position, as shown clearly in Figure 2. 30 designates a compression plate or washer which may be employed between the insulating member and the inner face of the head or enlargement 18 on the post 17. In order to lock the post 17 against rotation with relation to the sleeve 16, the ends of the post 17, which define the slot 24, may be bent outwardly, as indicated at 31 in Figure 2, by the insertion of a suitable instrument within the slot 24. 32 are openings or eyes formed in the outer

end of the sleeve 16, and by which the strain member may be attached to the cap of the adjacent insulating unit.

In Figure 8, I have shown a modified form 5 of construction, embodying a hollow support or tube 33, with an enlargement 34 at its inner end for engagement with the shoulder 35. The enlargement 34 is formed on the tube after the latter is positioned within the 10 insulator, by exerting sufficient fluid pressure within the tube and in such manner as to expand its outer end over the shoulder, thus holding the support engaged with the insulator. The outer ends of the tube 33 may 15 then be pressed together to provide a connecting portion 36, having the opening 37 therein. The tube is preferably filled with cement, or other analogous substance, after forming the enlargement at the inner end, in 20 order to afford a solid connection, and to withstand the necessary strains.

I claim as my invention:

1. In a strain insulator, the combination 25 with an insulating member having an angularly arranged interior shoulder, the angle of the said shoulder with reference to a plane at right angles to the normal direction of strain being not greater than forty-five degrees, of a strain member extending 30 interiorly of the insulating member and including a shouldered support, and retaining means for said support, said means including a plurality of cup shaped plates adapted to fit between the respective shoulders 35 formed on the insulating member and the said support.

2. In a strain insulator, the combination 40 with an insulating member having an angularly arranged interior shoulder, the angle of the said shoulder with reference to a plane at right angles to the normal direction of strain being not greater than forty-five degrees, of a strain member extending 45 interiorly of the insulating member and including a support, and retaining means secured to the support and including a plurality of

laminated plates provided with inclined or angular marginal portions extending parallel to and supported by the aforesaid shoulder and through which plates the support 50 extends.

3. In a strain insulator, the combination 55 with a frangible insulating member having an interiorly arranged and inclined shoulder, of a strain member extending interiorly of the insulating member and including a bolt provided with a conical head, and retaining means for said bolt, said means comprising a plate provided with an opening 60 to receive the stem of the said bolt and further provided with an inclined portion adapted when said means is in assembled position to extend parallel to the said conical face of the said bolt head.

4. In a strain insulator, the combination 65 with a frangible insulating member having an interiorly arranged and inclined shoulder, of a strain member extending interiorly of the insulating member and including a support, and retaining means secured to the 70 support and consisting of a plurality of laminated plates provided with expanded inclined or angular portions extending parallel to and supported by the aforesaid shoulder.

5. The combination with a frangible insulating member having a recess provided 75 with an interior inclined shoulder, of a strain member extending interiorly of the insulating member and including a support 80 having a head provided with an inclined shoulder, said head being of smaller diameter than the mean diameter of the recess, and retaining means secured to the support and embodying a washer beneath the head having 85 a marginal portion expanded by engagement with the shoulder on the head to lock with the shoulder on the insulator member.

WALTER T. GODDARD.
